BOLT OPERATING MECHANISM FOR
REPEATING SHOTGUNS

Frank T. Green, Chicopee Falls, Mass., assignor
to Savage Arms Corporation, Utica, N. Y., a
corporation of Delaware

Application January 8, 1948, Serial No. 1,092

1 Claim. (Cl. 42—21)

1

This invention relates to improvements in repeating shotguns and has for its object provision for a new construction of the bolt operating mechanism with a view to simplifying the same, providing a strong and durable structure to reduce costs.

A further object of the invention is to provide on said bolt mechanism for a magazine shell stop cooperating with other mechanism for convenience in manually loading shells in the magazine tube and for positively retaining the tube supply of shells therein during operation of the gun.

The full advantage of the invention will become apparent from the following and more detailed description taken in connection with the accompanying drawings, in which.

Fig. 1 is a side view showing the action bar structure in forward position;

Fig. 2 is a similar view with the casing broken away to show the parts in forward position, i. e. with the action closed;

Fig. 3 is a view similar to Fig. 2 with various parts in section and with the action open;

Fig. 4 is a perspective to show structural details of the bolt slide construction;

Fig. 5 is a section on line 5—5 of Fig. 4;

Fig. 6 is a side view with casing cut away to show the magazine loading operation;

Fig. 7 is a bottom view of the receiver; and

Fig. 8 is a side view with parts cut away to show the shell lifter mechanism.

Referring more particularly to the drawings, the receiver 1 (Fig. 1) is provided with the usual ejection port 2 and an action bar 3. The latter rides in a groove 4 cut in the inside surface of the receiver. It projects forwardly from the receiver and is formed with a handle 5 on a magazine tube 6 which is mounted below barrel 7.

As shown, the action bar 3 is provided with a notch 8 for receiving a lug 9 of the bolt slide to be described and for reciprocating the same in the receiver in operating the gun.

Lug 9 (Fig. 2) is an integral part of a bolt slide generally indicated by numeral 10. This slide is shown in perspective in Fig. 4. It is adapted to cooperate with a generally cylindrical bolt 11 and forms with it a two part bolt construction. On the underside of bolt 11 an intermediate flat portion 12 is cut between the ends thereof. Portion 12 is stepped as at 13, the forward part thereof being provided with a longitudinal slot 14 giving access to a notch 15 in a firing pin 16 set in a longitudinal bore of bolt 11. Notch 15 receives an upstanding post 17 of slide

2

10 in a manner which prevents operation of the firing pin 16 unless the action of the gun is closed as will become apparent.

Slide 10 rides with the action bar 3 in groove 4 and on its opposite side in groove 18 (Figs. 2 and 3) in the opposite inside surface of receiver 1. A rectangular opening 19 in the rear portion of slide 10 provides, with a rear stud 20 of bolt 11 inserted in said opening 19, an interlock between the two parts whereby movement of the slide 10 carries the bolt with it in the receiver as will be apparent. It will be noted that the end of bolt 11 is chamfered and provides on the stud a camming surface 21 to cooperate with a complementary rear edge surface 22 of opening 19. When the bolt mechanism is carried from the position of Fig. 3 to that of Fig. 2 by the action bar, bolt 11 is brought forward by the stud 20 in opening 19 of slide 10. As the action is closed bolt 11 is cammed upwardly at the rear thereof to be tilted into locking position. The front face 23 of bolt 11 is machined at an angle to bring said face flush against the opening of the breech. Upward thrust of the bolt permits the slight further travel of slide 10 and carriage of post 17 forwardly in slot 14 to free the firing pin 16 (Fig. 2).

On rearward travel to open the action a raised forward edge 24 of opening 19 in slide 10 catches the forward edge of stud 20 to cam bolt 11 downwardly and carry the parts to their relative position when open as in Fig. 3.

Slide 10 at its rear edge is also provided with a centrally upturned cam 25 to ride a hammer 26 (pivoted on the trigger assembly frame as at 27) back to cocked position as movement of bar 3 opens the action.

An action lock lever 28, pivoted at 29 on the trigger assembly frame, cooperates with a finger 30 on the rear edge of slide 10 to lock the bolt mechanism when in the locking or firing position of Fig. 2. As will be understood if it is not desired to fire the gun, pressure on finger piece 31 of lever 28 at the rear of the trigger guard carries the lever out of the path of finger 30 and permits the action to be freely opened by manipulating bar 3. When the gun is fired, lever 28 is automatically carried out of the path of finger 30 by release of the hammer. The action of hammer 26 with relation to the lock lever 28 is as follows. When the hammer is being cocked a stud 32 thereon rides under an upwardly projecting latch 33 of the lever 28. The latch 33 holds the hammer from being released while the bolt is being carried forward in the receiver. At

the time the bolt is finally closed finger 30 de-presses lever 28 at its forward end causing the latch 33 to slip under stud 32 for the firing position as shown by Fig. 2. Lever 28 is held in this upward position, as shown, by a spring 34 anchored in a slot 35 in the forward part of lever 28. The spring is turned to lie pressed downwardly against a stud 36 fixed on the hammer 26 thus urging lever 28 upwardly. As trigger 37, pivoted at 38, releases the hammer 26 to fire the gun, spring 34 is released by the changed position of stud 36, said stud striking the hooked end of the spring 34 to release the pressure thereof and lower lever 28 and its upper end out of the path of finger 30. Thus the action may then be opened after firing by manipulating action bar 3.

The trigger mechanism as shown also includes a trigger spring 39, a safety button 40, and a hammer spring assembly 41 all as will be readily understood.

A shell lifter 45 best shown by Fig. 8 is attached to the trigger assembly frame by an offset arm 46 pivoted as at 47. A spring pressed lifter pawl 48, mounted on the end of arm 46, is turned back against its spring 49 by slide 10 when the latter is moved rearwardly. Upon the return forward motion of slide 10, pawl 48 is caught in a notch 50 on slide 10 causing the shell lifter to tilt upwardly and be held in the position shown (Fig. 8) by a spring detent comprising a spring 65 and tooth 66. It will be understood this operation is for carrying a shell from the magazine tube and positioning it for carriage to the firing chamber after a previous shell has been fired and ejected by the opening of the action.

Bolt 11 is provided with the usual extractors 51. An ejector 52, shown by Fig. 6, kicks the shells out of port 2.

The shell stop mechanism and operation in reloading the gun from the magazine will now be described. Mounted adjacent the opening of magazine tube 6 in the receiver is a cartridge stop 53 formed by a strap of spring metal and having a release arm 54 disposed at right angles thereto in a recess 55. On the leading edge of slide 10 a cam surface 56 (see Fig. 4) is adapted to press the arm 54 in recess 55 when the bolt is forward, thereby permitting a shell to be pressed from tube 6 by a magazine tube spring 57 (shown by Fig. 6).

It will be seen from consideration of Fig. 2 that a shell pressed past cartridge stop 53 is caught by a shell stop 58 mounted on the front underside of slide 10. Said stop 58 is pivotally mounted on a bracket 59 as at 60 and is spring pressed outwardly thereof by a spring 61.

From consideration of Figs. 2 and 3 it will be noted that shell stop 58 is carried to the rear with slide 10, the shell following stop 58 until pushed by the magazine spring against a shoulder 62 of the lifter. Shells remaining in tube 6 are held by cartridge stop 53. As the lifter on forward travel of the bolt tilts the shell (Fig. 8) the bolt 11 pushes said shell into the chamber. Shell stop 58 then kicks the lifter 45 downwardly to disengage spring 65 and tooth 66 to spring press the lifter to the position shown by Fig. 2. Cam surface 56 on slide 10 again depresses cartridge stop 53. The next shell in tube 6 then is pushed past cartridge stop 53 contacting shell stop 58 in readiness for the next cycle of operation.

In addition to the function described above, a further advantage of the shell stop 58 is in the provision for facilitating the initial loading of shells in magazine tube 6 or for the unloading

of the same from the tube 6. Both of these operations are accomplished when the action is closed as in Fig. 6. The operator when inserting a shell in loading presses the same against the lifter which pivots against the spring detent arrangement 65 and 66 previously described. Lifter 45 (Fig. 7) is provided with a forked end to lie astride stop 58. Stop 58 is retracted to afford a guided passage for the shells into the tube. As a shell is placed against the lifter it is fed into the tube and when manually released is caught by stop 58, the lifter returning to normal position by pressure of spring 65.

In unloading the shells from the tube 6 finger or thumb pressure against the lifter 45 causes the shell stop 58 to be depressed out of the path of the shells, thus permitting the shells to be emptied from the tube by pressure of the tube spring. The cartridge stop 53 is inactive because the action is closed. It will be understood, furthermore, that the forked end of lifter 45 exerts a camming action in the unloading operation. The tips 67 being depressed under the rim of the shell, the inside surfaces of the forked portions tend to lift the shell outwardly of the receiver as the tube spring presses the same back along the lifter. Thus the simple action of pressing the lifter permits the ready emptying of shells from the tube.

It will be noted that with the arrangement of parts described the bolt structure with the slide 10 is extremely simple in character. Very little machining is required to form the bolt 11 which may be produced from round bar stock. The slide may be stamped from a rectangular piece of metal requiring but a few trimming cuts and the drilling of holes for attaching post 17 and bracket 59. The other parts as well may be for the most part simply formed from stampings, thus reducing production costs and resulting in a new construction of operating mechanism.

What I claim is:

The combination of a two part bolt mechanism with a repeating shotgun of the type having a receiver to contain a bolt for reciprocation therein, a spring loaded magazine tube for storage of shells opening into the receiver, a cartridge stop in the receiver adjacent the outlet of said tube and adapted to retain shells therein, firing mechanism with hammer and trigger mechanism, an action bar to reciprocate the bolt structure, and an action lock lever, said bolt mechanism comprising a generally cylindrical bolt member having a flat portion on its underside between its ends and forming a depending stud at the rear of the bolt, a slotted portion provided in the forward end of said flat portion, a bore longitudinally of the bolt and connecting centrally thereof with said slot, a firing pin mounted in the bore and having a recess on its underside accessible through said slot, and a one-piece bolt slide having a lug at the side thereof engageable with said action bar, an upstanding tapered post extending through said slotted portion of the bolt engageable with the firing pin recess to prevent operation thereof, an opening rearwardly of the slide to receive said depending rear bolt stud whereby on movement of the slide the bolt is carried in the receiver, the end of said stud being chamfered and said opening having a complementary rear edge for raising the end of said bolt upwardly in the receiver when the slide and bolt are moved forwardly, the forward edge of said opening having a raised surface to catch the forward end of said stud to cam the bolt downward on rearward travel of the slide, a finger

at the rear of the slide to engage with the action lock lever to lock the bolt when in firing position, a cam projection on the slide engaging the hammer on rearward travel of said slide to return said hammer to cocked position, a depending bracket at the forward end of the slide having a shell stop pivoted thereto with spring means to bias the shell stop outwardly of the bracket, and a cam surface at the forward end of the slide which, when the slide is forward, depresses said receiver cartridge stop and permits passage of a shell from the magazine tube past the cartridge stop for engagement by said shell stop.
